UNITED STATES PATENT OFFICE.

MONTRAVILLE E. PLATTS AND ALFRED F. NEBHUT, OF ILION, NEW YORK.

VEGETABLE SLICER.

Application filed November 22, 1922. Serial No. 602,616.

To all whom it may concern:

Be it known that we, MONTRAVILLE E. PLATTS and ALFRED F. NEBHUT, citizens of the United States, residing at Ilion, in the 5 county of Herkimer and State of New York, have invented certain new and useful Improvements in Vegetable Slicers; and we do declare the following to be a full, clear, and exact description of the invention, such as 10 will enable others skilled in the art to which it appertains to make and use the same.

This invention relates to improvements in slicing devices for vegetables, fruit, etc., and has for its principal object to provide 15 an extremely simple and inexpensive device, the greater part of which may be formed from metal stampings.

Another object is to provide novel means for automatically throwing the feed screw 20 out of play when the object being sliced has been advanced to the maximum.

With the foregoing in view, the invention resides in the novel subject matter herein-after described and claimed, the descriptive 25 matter being supplemented by the accompanying drawing.

Figure 1 is a side elevation partly in section of a slicer constructed in accordance with my invention.

30 Figure 2 is an upper edge view partly in horizontal section.

Figure 3 is a horizontal sectional view as indicated by line 3—3 of Fig. 1.

Figures 4 and 5 are vertical transverse 35 sections as indicated by lines 4—4 and 5—5 of Fig. 1.

Figure 6 is a fragmentary side elevation partly in section.

Figure 7 is a perspective view of the main 40 stamping.

Figure 8 is a perspective of the lever which co-operates with the feed screw.

In the drawings above briefly described, the numeral 1 designates a main stamping 45 formed from a single metal plate and including an upright body portion 2, an upper relatively long horizontal arm 3 and a lower shorter arm 4, the two arms extending in the same direction from one edge of the 50 body portion 2 and being disposed in the same vertical plane with said body portion. The lower edge of the upper arm 3 is provided with oppositely bent horizontal lugs 5 constituting feet adapted to rest upon a 55 table top while the free end of the horizontal arm 4 carries a clamping screw 6 to secure

said feet against the top of the table. This screw is threaded through a vertical bearing 7 formed by bending the free end of the arm 4 upon itself.

At its free end, the upper arm 3 is provided with a vertical post 8 which is disposed in a plane at right angles to the above mentioned vertical plane, said post carrying a slicing knife 9 which is secured flat against its inner 60 side. The upper end of the post 8 terminates in a horizontal integral prong 10 which extends toward the upper end of the upright body portion 2.

The numeral 11 designates a horizontal 70 stamped metal bearing which is secured by rivets 12 to the upper end of the body portion 2 of the stamping 1, said bearing slidably receiving a horizontal screw 13 having a stamped metal handle 14 at its rear 75 end, said handle however being preferably formed with a wooden hand-grip 15. The front end of the screw 13 rigidly carries a disk 16 which is disposed in a plane at right angles to the screw axis, circumferentially spaced portions of said disk being stamped laterally to form fingers 17 adapted to be forced into a potato or the like which is to be rotated against the blade 9 and fed thereto by the screw. The prong 10 is in alinement with the axis of the screw 13 and serves as a bearing about which the object being sliced, is rotated.

The numeral 18 designates a horizontal 80 lever fulcrumed at 19 upon the upper portion of the stamping 1, the front end of said lever being bent laterally as indicated at 20 and formed with screw threads 21 to engage the lower side of the screw 13. The rear end of the lever 18 extends upwardly 85 and then passes laterally across the screw in spaced relation therewith, as indicated at 22. The handle 14 is provided with an integral cam 23 adapted to strike the lever end 22 when the screw 13 has moved forwardly to the maximum, thereby rocking the lever 18 to disengage the screw threads 21 from the screw 13, discontinuing the feed, the slicing operation being then completed. Like the stamping 1, the handle 14, 90 and the disk 16, the lever 18 is stamped from 95 a single piece of metal.

It will be seen from the foregoing that 100 an extremely simple and inexpensive construction has been provided, yet it will be 110 highly efficient and in every way desirable. As excellent results have been obtained

from the exact details disclosed, we prefer to follow these details, but it is to be understood that within the scope of the invention as claimed, numerous minor changes may be made.

We claim:

1. A device of the class described comprising a metal stamping having an upright body portion and upper and lower arms extending at right angles therefrom in the same direction, said arms being disposed in vertically spaced parallelism, the free ends of said upper arm having an upstanding post disposed at right angles thereto and the upper end of said post terminating in an integral horizontal prong upon which an object may rotate, a knife carried by and secured flat against said post, means carried by said upper end of said body portion for holding and rotating an object to be sliced and feeding it to said knife, and means carried by said lower arm for clamping said upper arm against a table top or the like.
2. A device of the class described comprising a screw having means for holding an object to be rotated and fed thereby, a bearing in which said screw is slidably received, a lever fulcrumed between its ends

on said bearing and having threads at one end engaging the screw-threads, the other end of said lever being directed outwardly and then laterally so that it extends across said screw in spaced relation, and a cam carried by said screw to engage and lift said last named lever end and to release the opposite end of the lever from the screw when said screw is moved through the bearing a predetermined distance.

3. A device of the class described comprising a metal stamping having an upright body portion, an upper relatively long arm and a lower shorter arm extending in the same direction from said body portion and in the same vertical plane therewith, the lower edge of said upper arm having oppositely bent lugs forming feet to rest on a table top, the free end of said lower arm being bent to form a bearing, the free end of said upper arm having an upstanding post in a plane at right angles to said vertical plane, said post terminating in a horizontal prong extending toward the upper end of said body portion.

In testimony whereof we have hereunto affixed our signatures.

ALFRED F. NEBHUT.
MONTRAVILLE E. PLATTS.
